UNITED STATES PATENT OFFICE.

JOHN C. MARTIN, OF TERRE HAUTE, INDIANA.

DEVICE FOR HOLDING MILK BOTTLES OR THE LIKE.

1,407,432.

Specification of Letters Patent. Patented Feb. 21, 1922.

Application filed June 25, 1921. Serial No. 480,384.

To all whom it may concern:

Be it known that JOHN C. MARTIN, a citizen of the United States, residing at Terre Haute, in the county of Vigo and 5 State of Indiana, has invented certain new and useful Improvements in Devices for Holding Milk Bottles or the like, of which the following is a specification.

My invention relates to a device for receiving a milk bottle or bottles, or like articles and adapted when properly actuated, to prevent the removal of the same by an unauthorized person.

An important object of the invention is 15 to provide a device of the above mentioned character so constructed that a permanently open passage is provided for the insertion of the bottle or bottles into the same and to permit of the removal of the bottles only 20 upon opening a door which may be locked in the closed position.

A further object of the invention is to provide a device of the above mentioned character which may be permanently 25 anchored to a front porch or the like, so that it may not be readily removed.

A further object of the invention is to provide a device of the above mentioned character which is simple in construction, cheap 30 to manufacture, strong and durable.

Other objects and advantages of the invention will be apparent during the course of the following description.

In the accompanying drawing, forming 35 a part of this specification, and in which like numerals are employed to designate like parts throughout the same,

Fig. 1 is a horizontal section taken on line 1-1 of Figure 2,

40 Fig. 2 is a vertical section taken on line 2-2 of Figure 1,

Fig. 3 is a side elevation of the device, and,

45 Fig. 4 is a detail elevation of the catch or pawl device to prevent back turning of the rotatable carrier.

In the drawings, wherein for the purpose 50 of illustration is shown a preferred embodiment of my invention, the numeral 5 designates a preferably cylindrical casing, which is preferably vertically arranged, while I also contemplate arranging this casing horizontally. The vertical arrangement is preferred in as much as it eliminates any tendency for the contents of the bottles to spill. The casing 5 has a top 6 and a bottom 7,

as shown. Secured to the lower ends of the casing 5 are anchor elements or feet 8, which are adapted to be rigidly secured to the floor or a porch or the like, by means of 60 screws, or any other suitable means. The casing 5 which is stationary is provided in its side with a permanently uncovered opening or passage 9, which might be termed an inlet opening and also has an outlet opening 10, arranged at substantially an angle of 45° thereto, while this arrangement may be varied, as may be found advantageous. The opening 10 is adapted to be covered by a door 11, hinged to the casing at 12, and 65 carrying a hasp 13, to fit over a staple 14, rigidly secured to the casing, and adapted for the reception of the shackle of a padlock. Any other suitable means may be employed to lock the door in the closed position. 70

Arranged within the casing 5 is a rotatable carrier, which is also vertically arranged. This carrier embodies a central supporting element or post 15, having pivot elements 16 and 17 at its upper and lower 80 ends, pivotally mounted within openings 18, formed in the top and bottom 6 and 7, as shown. The post 15 is rotatable and the bottom or tray 19 of the carrier is attached to its lower end. The carrier is divided into 85 a plurality of compartments or pockets 20, by curved strips 21, extending generally radially. These strips have their intermediate portions attached to the post 15 by screws 22, and the strips are also connected 90 with each other, at 23. Brackets 24 are attached to the outer ends of the strip 21 and secured to the bottom or partition 19. The numeral 25 designates the upper set of generally radial partitions, similar to the partitions 21, and correspondingly arranged. The partitions or strips 25 are secured to the post 15 by screws 26, and the partitions or strips are also connected with each other, 95 at 27.

Arranged beneath and secured to the bottom or tray 19 are vertically swinging catches or pawls 28, Fig. 4, adapted to contact with stationary stops or trips 29, having upstanding ends 30. The stops 29 are rigidly 105 mounted upon the bottom 7 of the casing, and the upstanding ends 30 thereof face in a counter-clockwise direction.

The numeral 31 designates a stop element or abutment, arranged interiorly of the casing 5, between the openings 9 and 10, and secured thereto at 32. This stop element is 110

arranged between the upper and lower strips or partitions 21 and 25, in the path of travel of the bottle 33, or other receptacle, held within each pocket 20.

5 The operation of the device is as follows: The door 11 being normally locked in the closed position, the milk man may insert the bottle 33 of milk into the pocket 20, adjacent the opening 9, and then turn the carrier. The carrier is turned counter-clockwise, Fig. 1, and the pawls 28 co-act with the stops 29 to prevent the turning movement of the carrier in a reverse direction. When the carrier is turned sufficiently to 15 bring the bottle 33 opposite the outlet opening 10, this bottle will then be in proximity to or contact with the stop 31, and hence the carrier cannot be turned further in that direction. The authorized person may now 20 open the door 11 and remove the bottle through the opening 10.

It is to be understood that the form of my invention herewith shown and described is to be taken as a preferred example of the 25 same, and that various changes in the shape, size and arrangement of parts may be resorted to without departing from the spirit of my invention or the scope of the subjoined claim.

Having thus described my invention I 30 claim:

In a device of the character described, a casing having an inlet opening and an outlet opening, a door to close the outlet opening and adapted to be locked in the closed 35 position, a rotatable post arranged centrally within the casing and extending longitudinally thereof, said post being polygonal in cross section, substantially U-shaped brackets secured to the sides of the post and secured to each other and forming a plurality of pockets, a tray having a central opening to receive the lower end of the post and arranged beneath the said brackets and connected with the ends of said brackets, said tray being spaced from the bottom of the casing, a pawl arranged beneath the tray and pivotally connected therewith to swing vertically, a plurality of stops secured to the bottom beneath the tray to engage with said 40 pawl, a stop secured to the casing and projecting inwardly therefrom and arranged between the inlet and outlet openings, and means pivotally connecting the ends of said 45 post with the top and bottom of said casing. 50

In testimony whereof I affix my signature.

JOHN C. MARTIN.
